HARMONICA PLAYING COVER

Anthony Balint, New York, N. Y.

Application November 29, 1951, Serial No. 258,878

2 Claims. (Cl. 84—377)

1

This invention relates to devices for helping beginners in playing harmonicas, and in particular a U-shaped spring clip cover having an extension with openings therethrough corresponding with the openings of a harmonica and having a slide for closing and opening the openings and also lugs providing closures for some of the openings.

The purpose of this invention is to provide a mouthpiece or cover adapted to be slidably positioned on a harmonica whereby a beginner may start by playing one note, then two notes, then three, four and gradually five notes which may be considered as the average number of notes covered by the mouth of a player and after which the device may be discarded.

In the conventional method of playing a harmonica the mouth of a player covers a plurality of notes and it is difficult for a beginner to strike the exact note desired. For this reason it is difficult to follow a scale and, therefore, it is difficult to carry a tune. With this thought in mind this invention contemplates a cover in the form of a mouthpiece having means therein for blanking out all except one note whereby a beginner may play any note desired. The device also includes similar covers in which all except two, three, four and five notes are blanked out, whereby after mastering a cover for playing one note the different covers are used progressively.

The object of this invention is, therefore, to provide a device for assisting a beginner in playing a harmonica whereby the beginner may start by playing one, two, or any suitable number of notes.

Another object of the invention is to provide a beginner's helper for a harmonica that may readily be applied to harmonicas of different sizes and types without permanently attaching the device to the harmonica and without changing parts thereof.

A further object of the invention is to provide an improved mouthpiece cover for a harmonica with which one or more notes may be played at the same time, which is of a simple and economical construction.

With these and other objects and advantages in view the invention embodies a slider U-shape in cross section having spring arms positioned to engage opposite sides of a harmonica and a mouthpiece, also U-shaped in cross section extended from the slider and having spaced openings therein corresponding with the notes of the harmonica and also having means for blanking out some of the openings.

2

Other features and advantages of the invention will appear from the following description taken in connection with the drawings, wherein:

5 Figure 1 is a side elevational view showing a harmonica in an inverted position with the improved mouthpiece or cover on the under side thereof.

10 Figure 2 is a plan view illustrating the mouthpiece or cover with the harmonica omitted.

Figure 3 is a cross section through the cover taken on line 3—3 of Figure 2.

Figure 4 is a longitudinal section through the cover taken on line 4—4 of Figure 2.

15 Figure 5 is a detail illustrating a slide or gate for opening or closing openings through the cover.

Figure 6 is a view looking upwardly toward the under side of the cap or mouthpiece part of the cover with other parts omitted.

20 Figure 7 is a longitudinal section through the cover showing a lug blanking out one of the openings thereof.

Figure 8 is a similar section showing lugs blanking out two of the openings therein.

25 Figure 9 is also a similar section showing a further modification wherein all of the openings are blanked out by lugs except one opening in the center of the cap.

30 Figure 10 shows a further modification wherein three of the openings of the cap are blanked out.

Referring now to the drawings wherein like reference characters denote corresponding parts

35 the improved beginner's helper for playing harmonicas of this invention includes a cover 10 having spring clips 11 and 12 at the sides, a cap 13 having a continuous bead 14 around the open end thereof by which the cap is attached to

40 the cover 10, and a gate 15 having a projection providing a handle 16 at one end and having openings 17 extended therethrough and which are positioned to register with openings 18 extended through the cap 13 as shown in Figure 4.

45 In the design shown the base of the cover 10 is provided with an elongated channel 18 and the gate 15 is slidably mounted in the channel and resiliently held outwardly in the position shown in Figure 4 with a spring 19. One end of the spring is held against a lug 20 in the inner end of the channel and the opposite end extends into a slot 21 in the end of the gate 15. The gate is provided with an extended tongue 22 on which the projection or handle 16 is positioned.

The cap 13, which forms a mouthpiece, is provided with an end wall 23 in which openings 24 that register with the openings 17 and 18 are positioned and with the parts positioned as illustrated in Figure 4 the device is positioned on a harmonica, as indicated by the numeral 25, and the harmonica may be played in the conventional manner with the gate 15 actuated to regulate the size of the openings.

With the cap formed as illustrated in Figures 7, 8, 9 and 10 a cap 26, as illustrated in Figure 9 is provided with a single opening 27 and the openings at the sides are blanked out with lugs 28. By this means a mouthpiece is provided with a single opening and with this mouthpiece a beginner may play one note at a time, such as sounding the scale.

A similar cap 29 is provided in Figure 10, wherein the end surface of the cap is formed with openings 30 and 31 and the remaining openings are blanked out with lugs 32. By this means two notes may be played at a time.

In the design illustrated in Figure 8 a cap 33 is illustrated and this cap is provided with lugs 34 and 35 which blank out the end openings providing intermediate openings 36, 37 and 38 whereby three notes are played at a time.

And in the design illustrated in Figure 7 a cap 39 is provided with a single lug 40 whereby four openings 41, 42, 43 and 44 are provided.

With the parts formed in this manner a plurality of the covers may be included to form a set and with the caps illustrated in Figures 7, 8, 9 and 10 positioned on the slider 10 a beginner may first use the cover having a cap with one opening whereby one note may be played at a time.

After mastering the scales with one note the beginner changes to the cover having two openings in which two notes are played at a time and after mastering this scale the beginner continues with the cover shown in Figure 8 having three openings and after this stage the player progresses to the cover shown in Figure 7 having four openings, and eventually progressing to the cover illustrated in Figure 4 wherein five keys may be played at the same time and with use of the gate 15 these openings may be regulated as desired.

After playing with the cover having five openings the player may discard the device and play the harmonica directly with the mouth of the player covering as many openings as desired.

It will be understood that other modifications may be made in the design and arrangement of the parts without departing from the spirit of the invention.

What is claimed is:

1. A playing device for use on a harmonica comprising a cover U-shaped in cross section having spring actuated sides for frictionally retaining the device in position on a harmonica, a cap also U-shaped in cross section carried by the cover, said cap having a plurality of openings corresponding with notes of a harmonica extended therethrough, a gate slidably mounted in the cover and positioned to intercept the openings through the cap and a spring for retaining the gate in an extended position, said gate having openings therethrough positioned to register with openings through the cap, and the sliding movement of said gate regulating the areas of the openings through the cap as well as blanking off some of the openings in the cap.

2. In a beginner's playing device for use on a harmonica, the combination which comprises an elongated cover U-shape in cross section having spring actuated sides for frictionally retaining the device in position on a harmonica and having an elongated channel extended through the base thereof, a cap also U-shaped in cross section carried by the cover and extended outwardly therefrom, said cap having spaced openings extended therethrough and said openings positioned to correspond with notes of a harmonica, and a gate slidably mounted in the channel of the cover with a handle projecting at one end and having a plurality of openings therethrough corresponding with the openings extended through said cap, resilient means for actuating the gate in one direction and wherein the gate is adapted to be manually actuated in the opposite direction and means for blanking off openings of the cap.
